CLAIM

The ornamental design for a personal protective equipment as shown and described.

DESCRIPTION

FIG. 1 is an upper perspective view of a personal protective equipment in accordance with the present design;

FIG. 2 is a front elevation view of thereof;

FIG. 3 is a rear elevation view of thereof;

FIG. 4 is a left side elevation view of thereof;

FIG. 5 is a right side elevation view of thereof;

FIG. 6 is a top plan view of thereof;

FIG. 7 is a bottom plan view of thereof; and,

FIG. 8 is a lower perspective view thereof.

The features shown in broken lines in the various figures form no part of the claimed design. The shading shows contours, surfaces, or recesses of the present invention.

1 Claim, 7 Drawing Sheets
